UNITED STATES PATENT OFFICE.

SAMUEL BRACKSTONE, OF CORINTH, MISSISSIPPI, ASSIGNOR OF ONE-FOURTH TO FRANK B. ALLEN AND ONE-FOURTH TO EDWIN W. MITCHELL, OF CORINTH, MISSISSIPPI, AND ONE-FOURTH TO LOUIS H. HARRIS, OF ST. LOUIS, MISSOURI.

DISPLAY-STAND.

No. 848,718.

Specification of Letters Patent.

Patented April 2, 1907.

Application filed February 11, 1907. Serial No. 356,900.

To all whom it may concern:

Be it known that I, SAMUEL BRACKSTONE, a citizen of the United States, residing at Corinth, in the county of Alcorn and State of 5 Mississippi, have invented certain new and useful Improvements in Display-Stands; and I do declare the following to be a full, clear, and exact description of the invention, such as will enable others skilled in the art to 10 which it appertains to make and use the same.

This invention relates to display-stands, and has for its object to produce a device of this kind which will be simple and efficient 15 and is for the purpose of displaying articles, as hose, gloves, handkerchiefs, &c., and at the same time placing such articles in such a convenient position that the stand becomes a silent salesman as well as an advertising device. 20

One form of the invention is shown in the accompanying drawings, in which—

Figure 1 is a side elevation of the stand. Fig. 2 is a central vertical sectional view of 25 the same. Fig. 3 is an enlarged detail view of one of the holding-pins, and Fig. 4 is a perspective view of the same in use.

Referring more particularly to the drawings, which are for illustrative purposes only 30 and are therefore not drawn to scale, 1 indicates a standard provided with a base 2 and having a rod 3 projecting from its upper end.

Rotatably mounted upon the rod 3 is a suitable frame preferably comprising two 35 parallel bars 4 and 5, spaced apart, as by any suitable means, as a spindle 6, and mounted upon brackets 7. The brackets are joined at their lower ends by a sleeve 8, which is preferably rounded upon its lower end, as 40 shown at 9, for fitting in a corresponding recess 10 in the upper end of the standard 1.

Suitably mounted upon the upper bar 4 are supporting-pins 11, each of which is formed from two members 12 and 13, the central portions of which are joined to or connected with a support 14. The upper end of the support is provided with an enlargement or head 15, which is perforated angularly, if desired, as at 16, for the reception of the bar 4, which preferably corresponds in cross-section with the shape of the perforation 16, and a thumb-screw 17 projects into said perfora-

tion for securing the pin to the bar at any desired point. If desired, a support 18 may be secured to the head 15, so as to project upwardly for the purpose of holding an ordinary price-tag 19. The ends of the upper member 12 of the pin are bent downward and each provided with a hook 20 for the reception of the free end of the lower member or pin 13, 60 said end being preferably pointed for insertion through the articles to be suspended thereon, and the base of each pin or portion nearest the support 14 is provided with a coil 21 to afford greater spring or resiliency to the 65 pin. Normally the ends of the pin extend below the hook when released therefrom, as shown at 13' in Fig. 3.

Although I have shown the pins as adapted to be suspended upon the upper bar 4 of 70 a display-stand, it is evident that they can be secured at any other point in any desired manner, thereby permitting of their use independently of the stand, and other changes in the size, form, and construction of the different parts as will come within the scope of 75 the appended claims may be made without departing from the spirit of the invention.

When the invention is used as a display-stand, it can be placed in any convenient position, the base 2 being preferably provided 80 with rubber pads 22, and any desired number of pins can be placed upon the bar 4. In placing the articles upon the pins the free ends of the spring or pin members can be disconnected from the hooks of the upper or supporting members, and the articles placed thereon, either by having the pins passed through them or otherwise, after which said ends are replaced in the hooks. When ar-

ranged in this manner, the frame can be rotated so as to bring the articles upon either side of the bar into position for inspection by the would-be purchaser, thereby causing the stand to become a silent salesman, as it 95 were. After a selection has been made the desired article can be removed by releasing the point of the pin from the hook and then removing the desired article, after which the pin can be replaced in its hook in the same 100 manner as above described. The different parts of the stand can be made as ornamental as desired, thereby adding to its attractiveness without affecting its utility.

When the pins are used without the stand, they can be secured upon the other support by means of the thumb-screw in the same manner as upon the bar of the stand, and the articles can be attached thereto and removed therefrom in the same manner as though the pins were upon the stand.

Having thus described my invention, what I claim as new, and desire to secure by Letters Patent, is—

1. In a display-stand, a standard provided with an upright rod, a frame pivotally mounted thereon provided with a bar, a plurality of supporting-pins adjustably mounted upon said bar, said pins each comprising a support having a perforated head and two oppositely-extending members, one member being secured to the head and having its ends provided with depending hooks, and the other member being connected at its middle with the lower portion of the support and having its ends adapted to detachably engage with said hooks.

2. In a display-stand, a standard provided with an upright rod, a frame pivotally mounted thereon provided with a bar, supporting-pins adjustably mounted on said bar, each pin comprising two members, a support connected with the central portions of said members for engaging with the bar, the ends of one of the members being each

bent at an angle and provided with a hook, and the intermediate portion of the other member being bent into coils and having its ends adapted to be detachably engaged with 35 said hooks.

3. In a display-stand, a standard, the upper end of which is recessed, a rod extended upwardly from said standard, a frame rotatably mounted on said rod, comprising two bars spaced apart and brackets from the lower bar to the top of the standard, a sleeve at the inner ends of said brackets, the lower end of which is rounded to engage with the recessed portion of the standard, and supporting-pins upon the upper bar.

4. A display-pin, comprising two parallel members, each end of one of which is bent at an angle and provided with a hook and the ends of the other member are adapted to engage with said hooks, a support connected with the central portions of said members, one end of which is provided with a perforated head, and a thumb-screw projecting into said perforation.

In testimony whereof I have hereunto set my hand in presence of two subscribing witnesses.

SAMUEL BRACKSTONE.
